UNITED STATES PATENT OFFICE.

GEORGES DE ROUSSY DE SALES AND FRANÇOIS GUEUGNON, OF LYONS,
FRANCE.

ACCUMULATOR.

SPECIFICATION forming part of Letters Patent No. 696,496, dated April 1, 1902.

Application filed March 13, 1901. Serial No. 51,018. (No model.)

To all whom it may concern:

Be it known that we, GEORGES DE ROUSSY DE SALES and FRANÇOIS GUEUGNON, both citizens of the Republic of France, residing at 5 Lyons, in the Republic of France, have invented certain new and useful Improvements in Accumulators, of which the following is a specification.

This invention has for its object a novel 10 accumulator which is at the same time strong and light and which utilizes more completely and under the most favorable conditions the oxidizable and reducible metals commonly used in accumulators. We employ in such 15 accumulators plates either electrically or otherwise formed. Owing to the special arrangement of our accumulator, in which a metal tank lined throughout its whole inside surface with lead forms the anode, all faces 20 except one of the cathodes are utilized, each face of the cathode being adjacent to a face of the anode.

Our invention is illustrated in the annexed drawings, in which—

25 Figure 1 is a vertical sectional view of the anode. Fig. 2 is a section on the line C D of Fig. 1. Fig. 3 is a horizontal sectional view of said anode. Fig. 4 is a vertical sectional view of the accumulator. Fig. 5 is a section 30 on the line G H of Fig. 4, and Fig. 6 is a section on the line E F of Fig. 4.

The cathodes according to this invention consist of a supporting-frame 1, of aluminium, enveloped with a very thin sheet 2 of lead in 35 such a manner as to form an envelop or covering for the frame 1, as well as a plate surrounded by said frame. This frame 1 gives absolute rigidity to the sheet 2 of lead and induces conduction. The sheet or envelop 2 40 is perforated and provided on both of its external faces with metallic wires 3, thus forming a brush. After coating the sheet 2 with oxid of lead the cathode is rolled, which bends around the free ends of the wires 3, and so 45 that they hold the layer of oxid of lead to the plate. The plate thus formed is introduced into a suitably-perforated box 4, of ebonite, celluloid, or other insulating material. The cathode has upon its upper edge three projecting stems of aluminium cast in one with 50 the frame. The central stem 5 is screw-

threaded and provided with a nut in order to make connection. The anode is composed of an aluminium tank 6, having a flange for its suspension. This tank is divided up into 55 compartments by means of partitions of the same metal. The interior of the tank and the partitions are coated with a layer of porous or other lead 13 in such manner that each trough or compartment 7 forms the anode. 60 The assemblage of these compartments provided with their cathodes—that is to say, the entire tank—forms when coupled up an element, the connections being of course in parallel. Each tank is provided with a terminal 65 and a binding-nut, (not shown,) which serve to make connection. Inside each compartment 7 of the tank 6 we place two boxes 9 and 10, formed of perforated sheet-aluminium. These boxes are maintained at a suitable distance apart by distance-pieces 11, of ebonite or other suitable material. The outer box 9 is 70 in contact with the inner walls of the anode, while the inner box 10 forms a chamber 12 to contain the cathode, which fits into it. This 75 arrangement allows for changes in the volume of the cathode and avoids falls of oxid. The elasticity of the metal allows it to exercise a continuous pressure upon the sides of the cathode and of the anode, which prevents the 80 fall of powder when charging and discharging. The outer box 9, instead of being of aluminium, may be of ebonite or similar material, the volume of the anode being comparatively constant during work. The liquid elec- 85 trolyte is poured into the space comprised between the two concentric or nested boxes 9 and 10. In order to avoid movement of the liquid electrolyte when the accumulator is shaken, we render it immobile by means of 90 sawdust or maize powder or similar material 14, the absorption powers of which are considerable. A very small quantity of powder is necessary. This use of maize powder as an absorbent is known, but has never been 95 applied to accumulators to render the liquid electrolyte immobile.

Having thus described the nature and objects of our invention, what we claim as new, and desire to secure by Letters Patent, is— 100

1. In an accumulator, a cathode consisting of a supporting-frame of aluminium envel-

oped with sheet-lead said lead covering the frame and extending therefrom in the form of a plate surrounded by the frame, an anode composed of an aluminium tank divided into 5 compartments composed of the same metal, the interior of which tank is coated with lead so that each compartment forms the anode, two concentric or nested boxes having perforated walls separating the cathode from the 10 anode and an absorbent material, substantially as described, arranged between adjacent walls of said boxes, said material adapted to absorb and to render the liquid electrolyte immobile, substantially as described.

15 2. In an accumulator, a cathode consisting of a supporting-frame of aluminium enveloped with sheet-lead said lead covering the frame and extending therefrom in the form of a plate surrounded by the frame and provided 20 with metal wires forming a brush, an anode

composed of an aluminium tank having a flange for its suspension divided into compartments composed of the same metal, the interior of which tank is coated with lead so that each compartment forms the anode, two 25 concentric or nested boxes having perforated walls separating the cathode from the anode and an absorbent material, substantially as described, arranged between adjacent walls of said boxes, said material adapted to absorb and to render the liquid electrolyte immobile, substantially as described.

In testimony whereof we have signed this specification in the presence of two subscribing witnesses.

GEORGES DE ROUSSY DE SALES.
FRANÇOIS GUEUGNON.
